UNITED STATES PATENT OFFICE

DARIUS E. SHRAUGER, OF ATLANTIC, IOWA

SCREEN CONSTRUCTION

Application filed February 24, 1930. Serial No. 430,575.

The object of my invention is to provide a screen construction for windows which is simple, durable and comparatively inexpensive to manufacture.

5 A further object is to provide a screen construction consisting of supporting bars adapted to be secured to the sides of a frame of a window and a screen frame adapted to contact with the inner surfaces of the supporting bars whereby the screen frame may be installed in position or removed from the inside of a building.

10 A further object is to provide supporting bars with inwardly opening channels and a screen frame with flanges fitting into the channels to provide a fly tight joint which, however, provides for expansion and contraction of the window frame relative to the screen frame and for variation in the widths 20 of window frames to which the screen construction is applied.

15 Still a further object is to provide a screen frame having a section thereof hinged whereby the effective height of the screen frame may be reduced to facilitate mounting and tilting of the screen relative to the window frame.

25 With these and other objects in view my invention consists in the construction, arrangement and combination of the various parts of my device, whereby the objects contemplated are attained, as hereinafter more fully set forth, pointed out in my claims, and illustrated in the accompanying drawings, in which:

30 Figure 1 is an outside elevation of a window frame showing my screen construction applied thereto.

35 Figure 2 is an enlarged sectional view on the line 2—2 of Figure 3.

40 Figure 3 is a sectional view on the line 3—3 of Figure 1 illustrating the screen being installed.

45 Figure 4 is an enlarged sectional view on the line 4—4 of Figure 1 and

50 Figure 5 is an inside elevation of one of the lower corners of the screen construction.

On the accompanying drawings I have used the reference numeral 10 to indicate the sill of a window frame of the ordinary dou-

ble sash type. The side jambs thereof are indicated at 12. The lower cross bar of the upper sash of the window is indicated at 15.

55 My screen construction consists of a pair of supporting bars A and a screen frame B. Each supporting bar A has an attaching flange 14 adapted to be secured to the side jambs 12 (such as to the blind stop 16 thereof) by means of screws or the like 18. Each supporting bar A further includes a vertical channel portion 20 terminating at its upper end in a stop flange 21.

60 The screen frame B is preferably of sheet metal construction as fully described in my co-pending application, which issued into 65 Patent No. 1,779,859, under date of Oct. 28, 1930. It includes a screen covering 22 and a movable section 24. The movable section 24 is hinged as indicated at 26 to the screen frame B.

70 The section 24 of the screen frame B is provided with an upper flange 28 adapted to contact with a flange 30 of the screen frame B when the screen construction is in installed position as shown in Figure 2. A sill flange 32 is provided on the lower edge of the section 24 and the section is provided with a pair of handles 34. A latch 36 is provided for each side edge of the screen frame B and section 24 as will hereinafter be fully 75 set forth.

Practical operation

80 In the practical operation of my device, assuming it to be installed as shown in Figure 85 2, it will be seen that the inner face of the upper end of the screen frame B contacts with the outer face of the cross bar 15 of the upper sash of the window. The sill flange 32 contacts with the sill 10 of the window frame. This excludes the entrance of flies at the top and bottom ends of the screen frame B. Flies are excluded at the side edges by means of flanges 38 which fits into the comparatively wider channels 20.

90 95 The effective height of the screen frame B may be shortened to facilitate removal of the screen frame from the supporting bars A by swinging the hinged section 24 to the dotted line position shown in Figure 2. First of 100

all, however, the screen frame B must be raised until the upper end thereof contacts with the stop flanges 21 of the supporting bars A whereupon there will be sufficient clearance to swing the hinged section 24 as shown by dotted lines in Figure 3 and indicated by the arrow 40. The effective height of the screen frame B is now shortened so that it can be lowered to a position where the upper end thereof is no longer in contact with the cross bar 14. The screen frame B may then be swung inwardly as shown in the full line position in Figure 3, the hinged section 24 also shortening the length of the screen B for the purpose of clearing the stool 42 of the window frame. In replacing the screen frame, the operations above outlined are reversed.

It will be seen that provision has been made to use the cross bar 15 as a shield against the entrance of flies and that further means has been provided to allow the screen frame to be moved out of contact with this bar so that the screen frame can swing inwardly for removal of the screen from the supporting bars A. This is desirable as, if the screen height were not shortened, the lower end could not be pulled inwardly without the screen pivoting on the lower outer edge of the cross bar 14 and springing the supporting bars A out of shape.

Although I have illustrated a screen covering for the frame B, glass may be used instead whereby a conveniently installable storm sash is provided. The construction may be used on full window frames where other than a double sash window is used as well as on the half window illustrated.

Some changes may be made in the construction and arrangement of the parts of my device without departing from the real spirit and purpose of my invention, and it is my intention to cover by my claims, any modified forms of structure or use of mechanical equivalents, which may be reasonably included within their scope.

I claim as my invention:

1. In a screen construction for a window having a cross bar, a pair of supporting bars adapted to be secured to the sides of the frame of said window, a screen frame adapted to contact with the inner surfaces of said supporting bars and the outer surface of said cross bar, and thus be confined against both outward and inward movement respectively at its upper end and means to retain it against the supporting bars at its lower end, said screen frame having a section thereof movable with respect to the remaining portion thereof whereby it may be shortened to lower it from contact with said cross bar whereby it may thereafter be removed inwardly from contact with said supporting bars.

2. In a screen construction for a double sash window, a screen frame, means for sup-

porting the same with its upper end in contact with the outer face of the lower cross rail of the upper sash, said screen frame having a movable portion which contacts with the sill of the frame of said window when in one position and shortens the height of the screen frame when in another position whereby the screen frame may be lowered from contact with said cross bar and then swung inwardly under the same for removing it from installed position.

3. In a screen construction for a double sash window, a screen frame, means for supporting the same comprising supporting bars adapted to be secured to the sides of the frame of said window, said screen frame having its upper end in contact with the outer face of the lower cross rail of the upper sash and its outer face in contact with the inner faces of said supporting bars and thereby confined therebetween, and means for shortening the effective height of the screen frame whereby it may be lowered from contact with said cross bar and thereafter moved inwardly from contact with said supporting bars.

4. In a screen construction for a window having a cross bar, a pair of supporting bars adapted to be secured to the sides of the frame of said window, a screen frame adapted to contact with the inner surfaces of said supporting bars and the outer surface of said cross bar and be confined therebetween at its upper end, and manually operable means to retain the lower end of the screen frame in contact with the supporting bars said screen frame being confined between said manually operable means and the supporting bars.

Des Moines, Iowa, February 13, 1930.
